UNITED STATES PATENT OFFICE.

WILLIAM FAHRNEY, OF MILLEDGEVILLE, ILLINOIS.

WHIP-OPERATING DEVICE.

SPECIFICATION forming part of Letters Patent No. 782,227, dated February 14, 1905.

Application filed October 17, 1904. Serial No. 228,767.

To all whom it may concern:

Be it known that I, WILLIAM FAHRNEY, a citizen of the United States, residing at Milledgeville, in the county of Carroll and State 5 of Illinois, have invented certain new and useful Improvements in Whip-Operating Devices; and I do declare the following to be a full, clear, and exact description of the invention, such as will enable others skilled in the 10 art to which it appertains to make and use the same, reference being had to the accompanying drawings, and to the figures of reference marked thereon, which form a part of this specification.

15 My invention has reference to whip-operating devices, and pertains more specially to means for applying the whip to the lead-horses of a four-horse team attached to a machine or vehicle the driver of which is too far in the 20 rear of the lead-team to reach them with a whip in the usual manner.

In the drawings, Figure 1 is a side elevation of my device. Fig. 2 is a plan view thereof. Fig. 3 is a cross-section in the line 3 3 of 25 Fig. 2 looking from the rear. Fig. 4 is an enlarged detail of the swivel-block 4.

1 represents the front end of the tongue of the machine, upon which is secured a metal support 2, provided on each side with a laterally-extending arm 3, integral therewith. To the front end of the support 2 is pivoted a swivel-block 4, in which is pivotally supported a whip-socket 5, adapted to hold a whip 6. By means of a set-screw 7 in the wall of the 35 socket the accidental release of the whip therefrom is prevented. The lower end of the socket 5 is projected downwardly into a tapering shank 8, to the end of which is attached a pair of cords 9, which pass rearwardly through eyebolts 10, fixed in the arms 3, near the ends thereof, and thence to a point convenient to the hand of the driver.

A metal frame 11 is secured at its ends to the eyebolts 10 and extends forwardly and 45 downwardly, encircling the shank 8. At its central part the frame 11 is provided with an angular portion, in which the shank 8 normally rests, and from its points of support such frame is projected outwardly slightly 50 beyond the ends of the arms 3 to furnish

guards for such arms and prevent the interference thereof with the reins or other parts of the harness.

Fixed on the support 2 in rear of the arms 3 is a short post 12, to which is fastened one 55 end of a contractile coiled spring 13, the other end thereof being secured to the socket 5 above the pivotal point thereof. By this means the perpendicular position of the socket and whip is normally secured. 60

When it is desired to use the whip on the lead-horse on the left, the right-hand cord 9 is pulled by the driver, drawing the shank 8 rearwardly and tilting the upper part of the socket forwardly and downwardly. In its 65 rearward movement the shank 8 follows the inner side of the frame 11 on the right, as shown in Fig. 2, by which movement the swivel-block 4 and socket 5 are tipped toward the left. The combined downward and side 70 movement of the socket causes the whip to strike the horse on the left in the lead-team. Upon the cord 9 being released the whip is returned to its former position by means of the spring 13. To cause the whip to strike the 75 lead-horse on the right, the left-hand cord 9 is pulled, producing an operation similar to that just described, but toward the right-hand side. The degree of force which is given to the whip is entirely within the control of the 80 driver and can be made light or heavy to suit the disposition of the horse receiving the blow.

What I claim as my invention, and desire to secure by Letters Patent of the United States, 85 is—

1. A whip-operating device, comprising a support, adapted to be mounted on the tongue of the machine; a swivel-block pivotally secured to the forward end of such support; a 90 whip-socket, pivotally secured in such swivel-block; a tapering shank, depending from such whip-socket, and integral therewith; a frame, suitably supported on the device, and engaging the shank of the whip-socket; means for 95 moving said shank rearwardly and laterally, in contact with said frame, to one side or the other, as desired; and means for returning the whip-socket to its normal position, substantially as shown. 100

2. In a device of the class named, the combination of the support 2, suitably mounted on the tongue of the machine; arms 3, projecting laterally from such support; swivel-block 4, secured to the front end of the support 2; the whip-socket 5, pivotally secured in the swivel-block 4, and provided at its lower end with the shank 8; the frame 11, secured at the ends of the arms 3, and encircling the shank 8; means for drawing the lower end of the socket 5 rearwardly along the frame 11, to the right or left, as desired; and means for returning the socket 5 to a perpendicular position, substantially as shown and described.
- 15 3. In a device of the class named, the combination of the support 2, suitably mounted on the tongue of the machine; the arms 3, pro-

jecting laterally from the support 2; the swivel-block 4, secured to the front end of the support 2; the whip-socket 5, pivotally secured in the swivel-block 4, and provided at its lower end with the shank 8; the frame 11, secured at the ends of the arms 3, and encircling the shank 8; the cords 9 9, secured to the end of the shank 8, and supported in guides 25 in the arms 3; and the spring 13, mounted on the support 2, and secured to the socket 5, substantially as shown and set forth.

In testimony whereof I affix my signature in presence of two witnesses.

WILLIAM FAHRNEY.
